CLAIM

The ornamental design of a FIG. 1 is a semi cylindrical shaped toilet and rectangular prism shaped tanks combinations.

DESCRIPTION

FIG. 1 is a perspective view of a first embodiment of a semi cylindrical shaped toilet and rectangular prism shaped tanks combinations showing my new design;

FIG. 2 is a side elevation view, the opposite side being a mirror image, thereof;

FIG. 3 is a front elevation view thereof;

FIG. 4 is a rear elevation view thereof;

FIG. 5 is a top plan view with the lid closed thereof;

FIG. 6 is a bottom plan view thereof;

FIG. 7 is a perspective view of a second embodiment of a semi cylindrical shaped toilet and rectangular prism shaped tanks combinations showing my new design;

FIG. 8 is a side elevation view, the opposite side being a mirror image, thereof;

FIG. 9 is a front elevation view thereof;

FIG. 10 is a rear elevation view thereof;

FIG. 11 is a top plan view with the lid closed thereof; and,

FIG. 12 is a bottom plan view thereof.
